(57) **CLAIM**

The ornamental design for a broom, as shown and described.

DESCRIPTION

FIG. 1 is a perspective view of a broom showing my new design;

FIG. 2 is a front view of the broom shown in FIG. 1, the back view being identical; and,

FIG. 3 is a left side view of the broom shown in FIG. 1, the right side view being identical.

The broken line showing on the drawing disclosure is for illustrative purposes only and forms no part of the claimed design.
